UNITED STATES PATENT OFFICE.

JOSEPH TILDEN, OF JOHANNESBURG, CALIFORNIA.

HORSE-COVER.

No. 918,796.

Specification of Letters Patent.

Patented April 20, 1909.

Application filed October 6, 1906. Serial No. 387,763.

To all whom it may concern:

Be it known that I, JOSEPH TILDEN, a citizen of the United States, residing at Johannesburg, in the county of Kern and State 5 of California, have invented a new and useful Improvement in Horse-Covers, of which the following is a specification.

This invention relates to horse cover supports and more particularly to a support 10 carried by the shaft for the same; the object being to provide the shafts of a buggy or wagon with a frame adapted to fit over the horse and under its belly, so that a rubber, 15 canvas or net work covering can be readily secured over the same so as to protect the horse from sun, rain, snow and insects.

Another object of my invention is to provide the fastening bolts with hooks so that the covering can be readily secured therein 20 without any danger of it coming off.

Another object of my invention is to provide the hood of the frame with a hinge-joint so that it can be readily folded back when desired.

25 With these objects in view, the invention consists in the novel features of construction, hereinafter fully described and pointed out in the claims.

In the drawings forming a part of this 30 specification:—Figure 1 is a perspective view of a horse and a portion of the shafts showing my improved cover support attached. Fig. 2 is a transverse section through the shafts showing the manner of securing the frame to 35 the same. Fig. 3 is a perspective view of the snap hook and a portion of the frame showing the manner of securing the frame together at the front. Fig. 4 is a detail view of a portion of the frame showing the hinge- 40 joint of the hood. Fig. 5 is a section taken on lines 5—5 of Fig. 4.

In the drawings A indicates an ordinary pair of shafts, to which my improved cover support is adapted to be secured. The support 45 consists of the upper frame C adapted to extend over the back of the horse, the hood frame D adapted to fit over the head of the horse and the lower frame E adapted to fit under the belly of the horse.

50 The upper frame C is formed of a series of bowed strips C' having angled apertured ends C², which are secured to the top of the shaft by eye-bolts F. A bowed strip C³ is riveted to the strip C' adjacent their ends

being provided with a loop G at one end, and 55 the other end with a snap-hook H, for connecting the ends together. The ends of a bowed strip C⁴ are riveted to the strap C³ adjacent the ends having a strip C⁵ connected centrally to the same, extending backwardly 60 over the strips C' and riveted thereto, the end of the strip being riveted to the strip C³ midway of its length. A bowed strip C⁶ having its ends riveted to the strip C⁴ extends around the strip C' and strip C⁵ and is 65 riveted to the end strip when it crosses the same. Riveted to this strip is a bowed strip C⁷ having its ends connected to the strip C³.

The hood D consists of the bowed strips 70 D', D², D³, having the ends connected to a hinged plate D⁴, by rivets, which are hinged to plates D⁵ riveted to the bowed strip C⁴. These strips are connected together centrally by a strip D⁶. A bowed strip D⁷ is riveted 75 to the strip C⁴ to which is secured a flexible cable D⁸ one end of which is secured to the strip D⁶ and the other to the strip C⁵ so that the hood can be swung back off the head when desired. 80

The lower frame E consists of bowed strips E', having angled apertured ends which are secured on the end of the forward bolts F by hook-nuts F', and has riveted centrally thereto a strip E² provided with 85 back-strips E³ having angled apertured ends which are secured on the rear bolts F by nuts F'.

The strip E' and back-strip E³, are connected together by strips E⁴ adjacent their 90 ends which carry a bowed strip E⁵ which is riveted to the strip E². It will be readily seen that this frame can be readily attached after the horse has been harnessed. The covering I to be used will be provided with 95 hooks I' adapted to fit in the eye-bolt and hook-nut so that they can be easily and quickly attached or detached when desired.

It will also be understood that these frames can be made in different sizes so that they 100 will fit different size horses and shafts.

Having thus fully described my invention what I claim as new and desire to secure by Letters Patent is:—

1. In a device of the kind described, the 105 combination with a pair of shafts, of an upper and lower frame secured to said shaft, a hood frame pivoted to the upper frame hooks car-

ried by said shafts and a cover adapted to be secured to said hooks for the purpose described.

2. In a device of the kind described, the combination with a pair of shafts, of a series of bowed strips provided with outwardly projecting apertured ends secured on the top of the shafts by eye bolts, a bowed strip connecting the first mentioned bowed strips adjacent their ends and a loop secured to one end of said bowed strip and a hook to the other end of said strip, for the purpose described.

3. In a device of the kind described, the combination with a pair of shafts, of a plurality of bowed strips connected to the upper side of said shafts forming a frame, a hood pivotally connected to said frame, said hood being supported by a flexible cable, and bowed strips secured to the under side of said

shaft forming a frame, and a cover adapted to fit over and below the upper and lower frames and over the hood.

4. A horse cover of the kind described comprising a frame adapted to be secured on the upper side of a pair of shafts, formed of a plurality of bowed strips, a frame secured to the under side of said shaft formed of bowed strips, a hood formed of a plurality of bowed strips, carried by a plate, said plate being pivotally connected to a plate carried by the first mentioned frame, a cover arranged over said frame, a flexible cable connecting the bowed strips of said hood to the first mentioned frame, for the purpose set forth. 25 30

JOSEPH TILDEN.
